ATTORNEY.

UNITED STATES PATENT OFFICE.

WILLIAM J. SMITH, OF HUDSON TOWNSHIP, LAPORTE COUNTY, INDIANA.

COMBINED CONTAINER AND CARRIER FOR ICE-CREAM CONES.

1,176,932.

Specification of Letters Patent. Patented Mar. 28, 1916.

Application filed July 28, 1915. Serial No. 42,344.

To all whom it may concern:

Be it known that I, WILLIAM J. SMITH, a citizen of the United States, residing in Hudson township, in the county of Laporte and State of Indiana, have invented certain new and useful Improvements in Combined Containers and Carriers for Ice-Cream Cones, of which the following is a specification.

My invention relates to a carton or box 10 for packing cake cones, more commonly known as ice cream cones, and which are used for dispensing ice cream in small quantities at refreshment stands.

The primary object of the invention 15 relates in the provision of a carton or box in which a quantity of ice cream cones may be packed for shipment and handling in a sanitary manner, and at the same time form the carton in a manner so that the same may 20 be utilized as a carrier for easily and conveniently handling a number of filled cones without danger of spilling the contents. As 25 a filled ice cream cone will not remain upright unless carried in the hand or otherwise supported, and as there is more or less difficulty in properly carrying a number of the cones with the hands at one time, the present invention contemplates the use of the 30 carton in which the cones are packed by the producer as a carrier for the cones when filled, and this without adding to the cost of the carton.

The invention in the preferred form of 35 details will be described in the following specification, reference being had particularly to the accompanying drawings, in which:—

Figure 1 is a plan view of the carton blank before being folded. Fig. 2 is a perspective view showing the blank folded. Fig. 3 is a side elevation partly in section, showing the application of the invention. Fig. 4 is a fragmentary perspective view of 45 the invention.

Referring now particularly to the several views of the drawing, 1 designates a foldable blank of card-board or other suitable material, which is scored in the manner indicated by dotted lines 2, to facilitate folding thereof to provide a carton or box for the use of the manufacturer of the well known cones for dispensing ice cream, and in which the cones A may be packed and 55 protected against breakage in shipment and

handling, and kept in a sanitary condition as well.

My invention is applicable to any particular form and style of carton, and the manner of forming the carton blank is immaterial, a conventional form being illustrated merely for the purpose of showing the application of the invention without necessitating the use of additional material, or requiring the carton structure to be altered in any manner.

In the manufacture of the cartons, the blanks out of which same are formed are cut to form and scored by dies in a manner well known in the art, and in forming the 70 blanks I provide a series of relatively spaced slotted portions 3 on that part of the blank which will form one of the sides of the carton, as plainly shown in Fig. 2. Each slotted portion 3 consists of a plurality of radially 75 disposed slits, forming a plurality of flaps 4, which are bent inwardly in the act of forcing the small end of a cone through such slotted portion, and, owing to the resistance of the flaps to bend out of normal 80 position, provide a tight fit and grip between the cone and the flaps, so that with the end of the cone resting upon the bottom side of the carton, the cone will be tightly held in fixed relation with respect to the carton, so that a considerable number of filled 85 cones may be carried with the aid of the carton, and without danger of spilling the contents thereof.

As the flaps are not broken or bent down 90 until used as a carrier, as in the manner above described, the slotted wall of the carton remains intact, and serves the same function as a protection for the contents as though not slotted or prepared for serving 95 an additional function. The cartons now employed as a container for cones are discarded as soon as emptied of the cones, whereas my form of carton serves the additional function of serving as a carrier for 100 filled cones, and this without adding to the cost of manufacturing the cartons.

Referring to Fig. 4 which illustrates a modified form of the invention, it is seen that instead of providing the box with a 105 number of slits, circular or other formed openings 5 may be provided for receiving the end of the cone, but such is of practical use only where the cones used are all of a size, and the cones, which are top heavy 110

when filled, are not so firmly held as with the preferred form of structure first herein referred to.

While the foregoing is the preferred form of my invention, I desire it to be understood that I do not limit myself to the precise structure shown and described, as it is obvious that the same may be variously modified without departing from the spirit of the invention.

What is claimed is:-

1. A combined container and carrier comprising an enveloping carton to protect the cones against breakage and contamination, one of the walls of the carton being weakened at a plurality of points whereby the pointed ends of filled cones may be readily inserted into the carton through said weakened parts of the wall and supported in upright position by said wall to facilitate the carrying of the cones.

2. A combined container and carrier comprising an enveloping carton in which the

cones are packed and protected against breakage, one of the walls of the carton having a formation permitting the pointed ends of cones to be inserted through said wall into the container and supported thereby in an upright position.

3. A combined container and carrier comprising an enveloping carton to protect the cones against breakage and contamination, one of the walls of the carton having sets of grouped radial slits to weaken said wall at a plurality of points whereby the pointed ends of filled cones may be readily inserted into the carton through said weakened points and supported in upright position by said wall to facilitate the carrying of the cones.

In testimony whereof I affix my signature in presence of two witnesses.

WILLIAM J. SMITH.

Witnesses:

LELA W. COOK,
GEORGE J. OLTSCHE.
